John Saby, Jr. of Rochester, N. Y.
Assignor to

James R. Griffin, of Waterdown, Canada West.
Letters Patent No. 570 - Dated June 21st 1853.

The schedule referred to in these Letters Patent and making part of the same

To all whom it may concern:

Be it known, that I, John Saby, Jr. of the City of Rochester, County of Monroe, and State of New York, have invented or produced a new ornamental design for a stove plate known as the Kitchen Queen, and I do hereby declare that the following is a full and exact description of the same, reference being had to the annexed drawings, making a part of this specification, in which Fig. 1, is an elevation of my ornamental design for a stove plate.

Fig 2 is a section through A.B. Fig 1.

C, Fig 2, shows a section of the band shown C Fig 1. D, Fig 2, shows a section of the band shown D, Fig 1. - E, Fig 2, shows a section of the band shown

Wes. 510

~~120~~
E, Fig. 1. Fig. 2. shows a section of the hollow shown F. Fig 1. - G. Fig 2. shows a section of the quarter round on the edge of the oven door, shown G. Fig 1. H, Fig 2. shows a section of the hollow shown H, Fig 1. I. Fig 2. shows a section of the band shown I. Fig 1. - J. Fig 2. shows a section of the hollow shown J. Fig 1. K. Fig 2. shows a section of the bead shown K. Fig 1. I. Fig 2. shows a section of the hollow shown I. Fig 1. - M. Fig 2. shows a section of the flat surface of the door plate shown M. Fig 1. The parts marked N. Fig 2. show sections of the points marked N. Fig 1. The mouldings on the lower edge of the door are the same as those referred to by letters on the upper edge of the door. O. Fig 2. shows a section of the band shown O. Fig 1. - P. Fig 2. shows a section of the bead shown P. Fig 1. - Q. Fig 2. shows a section of the band shown Q. Fig 1.

What I Claim as my invention and desire to secure by Letters Patent, is the ornamental design of a stove plate, substantially as herein described and represented.
